US0D1008562S

(12) United States Design Patent (10) Patent No.: US D1,008,562 S
 Minorini (45) Date of Patent:  Dec. 19, 2023

(54) PACKAGING CASE FOR COSMETIC PRODUCTS

(71) Applicant: Euroitalia S.r.l., Cavenago di Brianza (IT)

(72) Inventor: Massimiliano Minorini, Milan (IT)

(73) Assignee: EUROITALIA S.r.l., Cavenago di Brianza (IT)

() Term: 15 Years

(21) Appl. No.: 35/513,128

(22) Filed: Jul. 29, 2021

(80) Hague Agreement Data

Int. Filing Date: Jul. 29, 2021

Int. Reg. No.: DM/217694

Int. Reg. Date: Jul. 29, 2021

Int. Reg. Pub. Date: Dec. 10, 2021

(51) LOC (14) Cl. 28-03

(52) U.S. Cl.

USPC D28/83

CPC A45D 33/20 (2013.01)

(58) Field of Classification Search

USPC D28/73, 76, 83-84; D9/430, 432, 428

CPC A45D 33/20; A45D 33/26; A45D 33/28;
